UNITED STATES PATENT OFFICE.

CARROLL DE ATLEY, OF BALTIMORE, MARYLAND, ASSIGNOR TO SUPERIOR STEAM IRON COMPANY, INC., OF BALTIMORE, MARYLAND, A CORPORATION OF MARYLAND.

PRESSING APPARATUS.

Application filed May 10, 1923. Serial No. 638,007.

To all whom it may concern:

Be it known that I, CARROLL DE ATLEY, a citizen of the United States, residing at Baltimore, State of Maryland, have invented 5 certain new and useful Improvements in Pressing Apparatus, of which the following is a description, reference being had to the accompanying drawing and to the figures of reference marked thereon.

10 The invention relates to new and useful improvements in a pressing apparatus, and more particularly to a pressing apparatus including a heated iron which is supplied with moisture at the ironing surface thereof.

15 An object of the invention is to provide an apparatus of the above type with means automatically controlled by the stand on which the iron is placed during idle periods, which cuts off the moisture supply from the 20 iron at such times.

A further object of the invention is to provide an apparatus of the above type wherein the moisture medium is automatically turned on when the iron is lifted from the stand.

25 A still further object of the invention is to provide an apparatus of the above type wherein the iron is heated by means contained therein, and through flexible connections with a source of supply, with means 30 for cutting down the supply of heat when the iron is placed on the supporting stand during idle periods, and for automatically turning on the heat when the iron is lifted from the stand.

35 A still further object of the invention is to provide an apparatus of the above type, which includes a supporting stand having means for collecting the moisture which may accumulate through a leakage valve or the 40 like.

45 A still further object of the invention is to provide an apparatus of the above type with a stand for the iron, which stand is provided with a downwardly curved ledge which aids in directing the iron on to the stand.

These and other objects will in part be obvious and will in part be hereinafter more fully disclosed.

50 In the drawings which show by way of illustration one embodiment of the invention—

55 Figure 1 is a view partly in perspective and partly in side elevation showing an apparatus embodying the improvements;

Fig. 2 is an enlarged view in side elevation showing the stand for supporting the iron;

Fig. 3 is a plan view of the same;

Fig. 4 is a view showing diagrammatically a modified form of controlling means for use in connection with the stand, and

Fig. 5 is a view more or less diagrammatic, showing a further modified form of the invention.

The invention is directed broadly to an apparatus which includes a pressing iron, which is preferably heated by means contained therein, which heating means is connected with a suitable source of supply 70 through flexible connections. The iron is also preferably provided with a moisture supplying means, which is likewise connected through flexible connections with a suitable source of supply.

In my prior Patent No. 1,447,535, granted February 6, 1923, I have shown such an apparatus. In my prior patent, treadle controlled means is also provided for cutting off the moisture when the iron is not in use 80 so as to prevent the condensate from accumulating in the iron and leaking therefrom. Such an apparatus is very efficient and very practical, but the operators, as a rule, do not like to use a treadle. In the apparatus of 85 my prior patent, unless the treadle is depressed when the operator takes the iron to do some pressing, no moisture will be turned on.

My present invention is directed to an improvement in the apparatus above referred to, and consists primarily in providing automatic means controlled by the weight of the iron, when set aside, which causes the moistening medium to be automatically turned on when the iron is picked up, for the pressing operation, and which automatically cuts off the moistening medium when the iron is set aside for an idle period. I have also provided means in the 100 preferred form of my invention, whereby the heating means is automatically cut down, through the weight of the iron when the iron is set aside. Thus it is that the iron is prevented from overheating and an 105 efficient control of the moistening medium is maintained.

Referring more in detail to the drawing, my improved apparatus consists of an iron 110 which as shown in Fig. 1, is of the gas

heated type and is preferably constructed as shown in my prior patent. A flexible tube 2 leads from a suitable air and gas supply 3, 4, respectively, which supply is controlled by suitable valves 5 and 6, respectively. The iron is also constructed so that steam may be applied thereto through a flexible pipe 7 which is connected with a supply pipe 8. Intermediate the supply pipe 8 and the flexible pipe 7 there is a hand valve 9 and also a quick controlled valve 10. Said quick controlled valve 10 is of the lever type, and the lever is normally raised by means of a spring 11 so as to open the valve and allow the steam to pass through into the iron. When the lever 10 is depressed, however, then the steam is cut off.

My improved apparatus includes a stand for the iron which consists of a platform 12 on which the iron may be placed, a raised side member 13 at the rear of the platform from the operator, and a raised end member 14. The platform is pivoted at 15, to suitable lugs 16 carried by a supporting base 17. A spring 18 normally holds said platform raised. The upward movement of the platform, of course, stops when the spring is expanded as far as it will expand and carry the weight of the platform. Said platform is also provided with a laterally projecting flange or ledge 20 which is turned downwardly as shown in the drawing, so as to direct the iron up on to the platform. It is well known that the operators in quickly handling the iron, will give the iron a more or less of a throw on to the platform, and in order to prevent the side of the iron from striking the edge of the platform, and thus marring the iron, this supporting ledge, which is curved downwardly, will usually catch the lower edge of the iron and direct the same up on to the platform. At the forward end of the platform, there is a projecting arm 21 connected by a flexible member 22 to the lever 10. It will readily be seen that when the iron is placed on this platform, the weight of the iron will depress the platform, compressing the spring 18. This will also pull down on the lever 10 and shut off the steam from the iron. When the iron is lifted from the platform, then the spring will raise the platform, releasing the lever and the spring 11 will raise the lever and turn on the steam.

In Fig. 4 of the drawings, I have shown a slightly modified form of the invention in that the stand is adjacent the supply pipes for the steam and gas. The gas may be led to the iron through a pipe 23, while the steam is led to the iron through a pipe 24. A valve 26 controls the supply of gas, and a valve 27 controls the supply of steam. Each valve is provided with an arm, which is pivotally connected to a rod 28, and the rod 28 in turn is pivotally connected to an

upwardly extending arm 29 carried at the forward end of the platform. It will readily be seen that when the platform is raised, the levers will be moved so as to turn the valves in one direction, and when the platform is depressed, then the valves will be turned in the other direction. The valves are so arranged that when the platform is raised by the lifting of the iron, both the gas and the steam are turned on to the iron, while when the platform is depressed through the placing of the iron thereon, the gas is cut down and the steam cut off.

In Figure 5 of the drawings, I have shown a slightly modified form of the invention in that electric means is used for heating the iron instead of gas. The heating means is of any well known construction, and the platform is constructed as above described in detail in connection with the gas supply, with the exception that there is a contact arm 30 which is connected to a wire 31 which leads to a resistance 32 and to the pressing iron. There is a contact 33 carried by the platform which in turn is connected to a line 34 connected with the other end of the resistance 32 and with the source of supply. There is a line 35 which leads from the source of supply to the pressing iron. It will readily be seen that when the platform is raised, the contacts 30 and 33 will be closed, thus shunting the resistance, and turning the full current through the iron, while, when the platform is depressed, the contacts 30 and 33 are separated and thus turns the current through the resistance, and therefore, cuts down its heating power.

While I have described the iron as supplied with steam for the purpose of providing a moistening means, it will be understood, of course, that I may connect the iron through a flexible pipe to a water supply, and depend upon the heat in the iron to transfer the water into steam for moistening purposes, and therefore, it is understood that the term "moistening means" as used in the description and claims is used in this broad sense.

It will be noted that directly beneath the platform there is a receptacle 36 formed in the base of the stand, and this receptacle is for the purpose of collecting any condensed moisture resulting from the cooling of the iron or the escaping of the steam, leaky valve or the like.

It is obvious that further modifications of the invention may be made without departing from the spirit of the invention as set forth in the appended claims.

Having thus described the invention, what I claim as new and desire to secure by Letters-Patent, is—

1. A pressing apparatus including a pressing iron, means for supplying moisture to the ironing surface of the iron, a sup-

porting stand on which the iron may be placed when not in use, said supporting stand having a movable platform, means for normally holding said platform in raised position, said means yielding to the weight of the iron when placed on the platform, said moisture supplying means including a valve yieldingly held open, and a connection between the valve and platform whereby when the platform is depressed by the weight of the iron the valve will be closed and the moisture supplied to the iron cut off.

2. In a pressing apparatus having a pressing iron and means for supplying moisture to the ironing surface of the iron,

a supporting stand on which the iron may be placed when not in use, said supporting stand having a hinged platform, a spring for normally holding said platform raised, the weight of the iron operating to depress the platform, said moisture supplying means including a valve, a spring for holding the valve raised in order to permit moisture to be supplied to the iron, and a flexible connection between the valve and the platform whereby when the platform is depressed and the iron is out of use, the moisture supplied to the iron will be cut off. 20 25

In testimony whereof, I affix my signature.

CARROLL DE ATLEY.
